UNITED STATES PATENT OFFICE.

LOUIS STEINBERGER, OF BROOKLYN, NEW YORK.

DISK STRAIN-INSULATOR.

1,212,706.

Specification of Letters Patent. Patented Jan. 16, 1917.

Application filed April 9, 1913. Serial No. 759,939.

To all whom it may concern:

Be it known that I, LOUIS STEINBERGER, residing at Brooklyn, in the county of Kings and State of New York, have invented certain new and useful Improvements in Disk Strain-Insulators, of which the following is a specification.

This invention relates to a disk type strain insulator and a principal object there-
10 of is to provide an insulator of this type which is flexible in its construction so that cables attached thereto may be allowed a slight degree of movement in the direction of their length without injury to the insulator.

A further object is to provide an insulator comprising opposed strain members and at least one of said strain members comprising a spring bar extending substantially trans-
20 versely of the direction of strain, and to form the body of the insulator so as to accommodate the flexing of said spring bar and limit said flexing.

A further object is to provide an insulator comprising a disk considerably wider than thick, to provide strain members disposed upon the opposite flat surfaces of said disk arranged in substantially right angular relation to each other in such position as to im-
30 part a crushing strain to the material of the insulator, and to provide housings formed on said disk for inclosing parts of said strain members.

A further object is to shape the opposite surfaces of the disk so that substantially only the central portions of said surfaces will engage adjacent central portions of the bars or strain members whereby the central portion only of said disk is normally sub-
40 jected to crushing strain.

A further object is to provide bails connected with the opposite ends of said bars or strain members adjacent the periphery of said disk, said bails having portions for the attachment of cables or the like and having intermediate portions, including the cable attaching parts, spaced a considerable distance from the surfaces of said disk.

A further object is to provide means upon the surface of the insulator for protecting the bars or strain members from moisture.

A further object is to provide reinforcing members upon the surfaces of the disk extending continuously across the periphery
55 thereof.

Other objects and aims of the invention

more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings, which are to be taken as a part of this specification and in which I have shown a merely preferred form of embodiment of the invention: Figure 1 is a top plan view of an insulator constructed in accordance with the principles of the invention. Fig. 2 is a side elevation view of the structure shown in Fig. 1. Fig. 3 is a transverse central sectional view taken substantially on the plane of line III, of Fig. 1. Fig. 4 is a fragmentary view similar to Fig. 3, but taken at right angles thereto and illustrating a modification; and Figs. 5 and 6 are detail fragmentary perspective views.

Referring to the drawings for a detailed description of the invention, the numeral 1 indicates a disk of insulating material, preferably electrose, the diameter of the disk being approximately though not necessarily four times the greatest thickness of the disk. 85 and the opposite surfaces of the disk being convex so that the marginal edges are relatively thin, as best seen in Fig. 2.

A plurality of reinforcing ribs 2 are formed upon the opposite surfaces of the disk extending continuously across the periphery thereof and for a distance inwardly toward the center of the opposite surfaces. These ribs preferably terminate short of the center so as not to interfere with the flow of moisture across the disk and to prevent the formation of pockets and the like. They also serve as barriers interposed between the ends of the strain members 3 peripherally of the disk.

Extending across the opposite surfaces of the disk centrally thereof, and arranged in substantially right angular relation to each other are the strain members or bars 3, the opposite ends thereof projecting beyond the periphery of the disk as at 4. Attached to the ends 4 are bails 5, the bails having apertures 6 for the reception of the ends 4, and said apertures preferably having flattened portions 7 for engaging flattened portions 8 of the ends 4. Suitable fastening means as nuts 9 are threaded or otherwise attached to

the ends of the strain members for retaining the bails against detachment.

In order to retain the strain members in their prescribed relations, suitable housings 5-10 may be molded as integral parts of the disk 1 if desired, the said housings inclosing the respective strain members in such manner as to provide, in effect, apertures 11 through which the strain members project.

10 In order that the strains applied to the strain members 3 may be transmitted to the material of the disk 1 centrally thereof I have formed the apertures 11 tapered in both directions outwardly from the central 15 portion, the central portion of the aperture being of a size to snugly receive the strain members, and the outer ends of the apertures being larger so as to accommodate a relative movement of the adjacent portions 20 of the strain members.

The strain members 3 are preferably slightly flexible and the looseness of the apertures 11 adjacent the ends of the strain members will permit of a limited degree of 25 flexing in the strain members as will be readily apparent from an inspection of Figs. 3 and 4. Strains applied to the ends of the strain members through the bails 5 therefore are absorbed to an appreciable degree 30 by the flexing of the two strain members within the body of the insulator without in any way affecting the integrity thereof. The direct strains between the two strain 35 members 3 are applied as a crushing strain between the central portions of the strain members only. Further strain upon the material of the insulator will only be sustained after a maximum amount of flexing has been given the strain members. The flexing 40 quality of the strain members 3 is preferably calculated so as to withstand a very great strain without imparting direct pressure from their ends against the adjacent walls of the apertures 11. In event that 45 such pressure does take place the force thereof will be already so spent as to be practically negligible and the material of which the disk is formed will be fully capable of resisting it.

50 The bails 5 have their intermediate portions, including a part 12 for the attachment of cables, spaced a considerable distance from the surfaces of the disk so as to preclude the possibility of arcing therefrom to 55 the disk or to the opposite strain member within the housing on the disk. The strain members 3 are preferably cylindrical and the apertures 11 likewise cylindrical so as to permit free swinging of the bail, the strain members serving as pivot rods for connecting the ends of the bail with the insulator.

60 In instances where the insulator is employed in such relation that its central axis is vertical, it may be desirable to provide a 65 petticoat 13 upon the under surface thereof,

this petticoat being preferably concentric with the disk and depending therefrom at or near the periphery thereof so as to intercept a flow of moisture along the under surface toward the lower strain member. 70 The disposition and relative proportions of the petticoat obviously also add materially to the mechanical strength of the insulator body.

75 It may be noted that the housings 10 extending across the opposite surfaces of the disk in right angular relation materially reinforce the disk in sustaining strains applied to it.

80 As many changes could be made in this construction without departing from the scope of the following claims, it is intended that all matter contained in the above description or shown in the accompanying drawing shall be interpreted as illustrative 85 only and not in a limiting sense.

Having thus described my invention what I claim as new and desire to secure by Letters Patent is:

90 1. A disk type strain insulator comprising a disk of insulating material, oppositely disposed strain members attached thereto, and strengthening ribs formed upon one surface of said disk, continuing across the periphery thereof, and continuing along the 95 opposite surface of said disk.

90 2. A disk insulator comprising a disk of insulating material and a plurality of strengthening ribs formed upon the upper surface of said disk radiating from the center thereof, continuing across the periphery thereof, and continuing along the opposite surface of the disk toward the center thereof.

100 3. A disk type insulator comprising a substantially flat body of insulating material, reinforcing members formed upon the opposite surfaces of said disk extending entirely across said surfaces, the reinforcing member upon one surface being in substantially right angular relation to the reinforcing member on the other surface of the disk, and strain members carried by said reinforcing members projecting beyond the periphery of the disk. 110

115 4. A disk type insulator comprising a substantially flat body of insulating material, reinforcing members formed upon the opposite surfaces of said disk extending entirely across said surfaces, the reinforcing member upon one surface being in substantially right angular relation to the reinforcing member on the other surface of the disk, and a plurality of reinforcing ribs formed upon the opposite surfaces of said disk radiating 120 from the center thereof.

125 5. A disk type insulator comprising a substantially flat body of insulating material, reinforcing members formed upon the opposite surfaces of said disk extending entirely across said surfaces, the reinforcing 130

member upon one surface being in substantially right angular relation to the reinforcing member on the other surface of the disk, means projecting from the ends of said reinforcing members adapted for the attachment of cables or the like, and reinforcing ribs formed upon said disk radiating from the center thereof.

6. A strain insulator comprising a body of insulating material, suspension means, a spring bar carried by said body disposed substantially transverse to the general line of strain, said spring bar being supported by its intermediate portion, and being connected with said suspension means by its opposite ends.

7. A strain insulator comprising a body of insulating material, suspension means, a spring bar carried by said body disposed substantially transverse to the general line of strain, said spring bar being connected at one point in its length to the suspension member and at another point in its length to the insulator body.

8. A strain insulator, comprising a disk of insulating material, a plurality of opposingly disposed strain members carried thereby, one of said strain members being disposed in substantially right angular relation to another of said strain members, each of said strain members being arranged to extend diametrically of the disk and having its opposite ends terminating adjacent the periphery of the disk, means for attaching conductors to the ends of the strain members, and barriers interposed between the ends of the strain members peripherally of the disk.

9. A strain insulator, comprising a disk of insulating material, a plurality of opposingly disposed strain members, each of said strain members comprising a rod arranged to extend diametrically of the disk, means for attaching conductors to the ends of the strain members, and barriers interposed between the ends of the strain members peripherally of the disk.

10. A strain insulator, comprising a disk of insulating material, a plurality of opposingly disposed strain members, each of said strain members comprising a rod arranged to extend diametrically of the disk, means for attaching conductors to the ends of the strain members, barriers interposed between the ends of the strain members peripherally of the disk, and said strain members being flexible so as to yield when strain is applied thereto from said conductor attaching means.

11. A strain insulator, comprising a disk of insulating material, a plurality of opposingly disposed strain members each of said strain members being arranged to extend diametrically of the disk and having its opposite ends terminating adjacent the

periphery of the disk, means for attaching conductors to the ends of the strain members, barriers interposed between the ends of the strain members peripherally of the disk, said strain members comprising normally straight rods of flexible material, and the surfaces of the disk underlying said rods being shaped to engage said rods at the central portions of said rods only so as to permit said rods to flex when strain is applied to the ends thereof.

12. In a strain insulator, a body of insulating material, a pair of strain members carried thereby, at least one of said strain members comprising a flexible rod adapted to be disposed transversely of the line of strain, and means for attaching conductors to said strain members, the conductor attaching means for said mentioned flexible strain member comprising a bail having portions extending to and connected with the opposite ends of said flexible strain member.

13. In a strain insulator, a body of insulating material, means for attaching conductors at opposite sides of said body of insulating material, at least one of said means comprising a bail having spaced leg portions and pivot means pivotally connecting said spaced leg portions with said body of insulating material, and means whereby said pivot means permits a limited movement between said body of insulating material and said bail in the general direction of strain.

14. A strain insulator, comprising a body of insulating material having convex opposite surfaces, a strain member extending diametrically across one surface of said body, a strain member extending diametrically across the opposite surface of the body, each of said strain members comprising a rod having its ends terminating adjacent the marginal edges of the body, conductor attaching means engaging the two ends of one strain member, conductor attaching means engaging the two ends of the other strain member, said conductor attaching means being disposed to urge the strain members toward the respective surfaces of the body, and both of said strain members being flexible and being in engagement with the respective surfaces of the body at their central portions only so as to be capable of flexing when strain is applied to the opposite ends thereof through said conductor attaching means.

15. A strain insulator, comprising a body of insulating material having convex opposite surfaces, a strain member extending diametrically across one surface of said body, a strain member extending diametrically across the opposite surface of the body, each of said strain members comprising a rod having its ends terminating adjacent the marginal edges of the body, conductor at-

taching means engaging the two ends of one strain member, conductor attaching means engaging the two ends of the other strain member, said conductor attaching means being disposed to urge the strain members toward the respective surfaces of the body, and both of said strain members being flexible and being in engagement with the respective surfaces of the body at their central portions only so as to be capable of flexing when strain is applied to the opposite ends thereof through said conductor attaching means, and means formed upon the opposite surfaces of the body for retaining the strain members against displacement.

16. A disk strain insulator comprising, a disk of insulating material of greater diameter than thickness adapted to be disposed substantially transversely of the general line of strain, bails arranged at opposite sides of said disk having portions extending to adjacent the periphery of the disk, strain members connecting said bails with said disk, said strain members comprising opposingly disposed rods extending diametrically of the disk, and the disk having parts formed thereon comprising housings for the strain members, said housings being disposed in substantially right angular relation to each other so as to retain the strain members in substantially right angular relation to each other.

17. A strain insulator, comprising a body of insulating material suspension means therefor, a member carried by the body to which said suspension means is attached, said member being flexible and being adapted to be flexed under stress from said suspension means, and said body having a part disposed to limit the flexing of said member.

18. A strain insulator, comprising a body of insulating material, a strain member car-

ried thereby comprising a rod arranged so as to extend substantially transversely of the general direction of strain when in use, a second strain member also arranged so as to extend substantially transversely of the general direction of strain when in use, said two strain members being arranged to extend in substantially right angular relation to each other, a portion of the insulating material of the body being interposed between said strain members and engaging said strain members at their central portions only, means for attaching conductors to said strain members, and said strain members being flexible to yield laterally under strain.

19. A strain insulator, comprising a body of insulating material, a strain member carried thereby comprising a rod arranged so as to extend substantially transversely of the general direction of strain when in use, a second strain member also arranged so as to extend substantially transversely of the general direction of strain when in use, said two strain members being arranged to extend in substantially right angular relation to each other, a portion of the insulating material of the body being interposed between said strain members and engaging said strain members at their central portions only, means for attaching conductors to said strain members, and portions of said insulating material being disposed to loosely surround said strain members to retain said strain members in substantially right angular relation.

In testimony whereof I affix my signature 80 in the presence of two witnesses.

LOUIS STEINBERGER.
